INVENTOR:

Lewis S. Chichester

United States Patent Office.

LEWIS S. CHICHESTER, OF BROOKLYN, NEW YORK, ASSIGNOR TO HIMSELF,
C. W. MILLS, AND G. H. NICHOLS, OF SAME PLACE.

Letters Patent No. 65,793, dated June 18, 1867.

IMPROVEMENT IN GRAIN-DRYERS.

The Schedule referred to in these Letters Patent and making part of the same.

TO ALL WHOM IT MAY CONCERN:

Be it known that I, LEWIS S. CHICHESTER, of Brooklyn, in the county of Kings, and State of New York, have invented, made, and applied to use a certain new and useful Improvement in Grain-Dryers; and I do hereby declare the following to be a full, clear, and exact description of the said invention, reference being had to the annexed drawing, making part of this specification, wherein—

Figure 1 is a vertical section of my improved grain-drying apparatus.

Figure 2 is a vertical section transversely of the fire-chamber; and

Figure 3 is a vertical section transversely of the grain-chambers.

Similar marks of reference denote the same parts.

In Letters Patent granted August 15, 1865, for a grain-dryer invented by me, a series of inclined tables is employed, and the heated air passes over the grain and beneath the next table above, so as to heat the tables and the grain, and convey away the moisture evaporated from the grain. And in Letters Patent granted May 2, 1865, for a grain-dryer invented by me, the tables upon which the grain falls are inclined, and alternately converge and diverge. My present invention is an improvement upon these said grain-dryers, and consists in a peculiar heating-chamber for the air that is passed to the grain; also in an arrangement of air-passages and

which it is allowed to run away at the lower part of the dryer, and by this means the extent of the drying operation may be regulated according to circumstances.

What I claim, and desire to secure by Letters Patent, is—

1. In a grain-drying apparatus I claim a chamber above the fire, into which air is admitted in large volumes, and descends and mingles with the products of combustion and passes into the grain-dryer, substantially as and for the purposes specified.

2. I claim the arrangement of the hot and cold-air flues *f* and *n*, trunks *g* or *g'*, and valves *l l'* and *m m'*, for regulating the temperature of the air passing into the grain-drying chamber *k*, substantially as specified.

3. I claim a series of half pipes crossing the grain-chamber, and opening at or near both ends into air-spaces or flues, as set forth, so that the current of air shall pass through and beneath the half tubes and in contact with the grain, as set forth.

In witness whereof I have hereunto set my signature this twenty-fourth day of November, A. D. 1866.

LEWIS S. CHICHESTER.
